PLATING APPARATUS

Daniel J. Borodin, Detroit, Mich., assignor, by mesne assignments, to Allied Research Products, Incorporated, Baltimore, Md., a corporation of Maryland

Filed Dec. 20, 1956, Ser. No. 629,659

29 Claims. (Cl. 134—164)

This invention relates to plating apparatus and more particularly to a means for agitating work pieces as the work pieces are conveyed through a series of plating tanks.

In some types of plating operations, there is a tendency for hydrogen bubbles to form on the work pieces being plated; and unless these bubbles are removed, an improper plate will result. One of the conventional ways of removing these hydrogen bubbles from the work pieces is to mechanically agitate the work pieces back and forth while they are conveyed through the plating solution so that the surfaces of the work pieces are constantly wiped by the solution.

In one type of plating apparatus such as illustrated in my co-pending application Serial No. 596,712, filed July 9, 1956, the work pieces are mounted on carriers slidably supported on rails mounted over and extending lengthwise of the plating tanks. With such an arrangement, a commonly employed method for agitating the work pieces comprises reciprocating the carrier supporting rails lengthwise of the tank. However, in arrangements of this type with which I am familiar, the rail supporting structure and the means for reciprocating the rails are rather cumbersome and inefficient. Furthermore, the conventional rail reciprocating mechanism usually involves numerous moving parts located directly above the plating tanks and subject to corrosion from the fumes of the plating solution. In addition, with conventional arrangements, warpage of the side walls of the plating tanks raises considerable problems relative to the proper alignment of the work supporting rails.

The present invention has for its object the provision of a rail supporting structure and a reciprocating mechanism for the rails that is of relatively simple construction, that eliminates the prior problems with reference to obtaining proper alignment of the rails and which is designed so as to substantially eliminate the problem of corrosion.

In the drawings:

Fig. 1 is a fragmentary perspective view of a plating tank provided with the rail supporting and reciprocating mechanism of the present invention.

Fig. 2 is a fragmentary perspective view showing a portion of the reciprocating mechanism.

Fig. 3 is a fragmentary cross sectional view of the rail supporting mechanism and taken generally along the lines 3—3 in Fig. 4.

Fig. 4 is a fragmentary side elevational view partly in section of a plating tank provided with the arrangement of the present invention and taken generally along the lines 4—4 in Fig. 3.

Fig. 5 is a sectional view taken along the lines 5—5 in Fig. 4.

Fig. 6 is a sectional view taken along the lines 6—6 in Fig. 3.

Fig. 7 is a sectional view taken along the lines 7—7 in Fig. 1.

In Fig. 1, a plating tank is illustrated at 10, one end

2

wall of the tank being designated 12. The side walls of the tank are provided along their upper edges with flanged supports 13 on which the rail supporting and reciprocating mechanism is mounted. The longitudinally extending work supporting rails are designated 14. Work carriers shown in broken lines at 16 in Figs. 3 and 6 are arranged to be slidably supported on rails 14. The means for advancing work carriers 16 along rails 14 comprise reciprocating pusher assemblies 18 (Figs. 3 and 6); and adjacent the end of each tank, an elevator structure (not shown) that is provided with lift angles 20 is arranged to engage the flanges 22 of work carriers 16 so as to lift the carriers and the work pieces supported thereby from the end of one tank and deposit them into the next adjacent tank on rails corresponding to the rails 14. The elevator structure and pusher assemblies are disclosed in detail in my said copending application Serial No. 596,712. Pusher assemblies 18, when actuated, are arranged to engage the work carriers 16 and slide them forwardly on the rails with a step-by-step movement.

The means for supporting rails 14 for reciprocation lengthwise of tank 10 include pairs of base plates 24 mounted one of each pair at each side of the tank on the flange supports 13 as by bolts 26. In the arrangement shown in Fig. 1, two pairs of such base plates 24 are illustrated; and since the construction at each of these base plates is identical, the description will be limited to one pair of base plates. On base plates 24 are arranged guide blocks 28. A movable bridge assembly 30 is mounted on guide blocks 28 for movement longitudinally of tank 10. More specifically, guide blocks 28 are each provided with a V-shaped groove 32 in which is arranged a stainless steel or ceramic ball 34 (Figs. 3 and 4). In any event, balls 34 are fashioned from a hard material that is substantially non-corrosive. Bridge assembly 30 includes a frame having upright legs 36 that are connected at their upper ends by means of a strut 38 which spans tank 10. A shoe 40 is secured to the lower end of one leg 36 and a shoe 42 is secured to the lower end of the other leg 36. In the showing in Fig. 1, shoe 40 is disposed at the near side of the tank and shoe 42 at the far side of the tank. The near side of the tank is at the outside of the machine where the tanks are arranged in an endless path. Shoe 40 is fashioned with a V-shaped groove 44 whereas shoe 42 is merely provided with a flat under surface 46 (Fig. 3). The groove 44 and the flat surface 46 engage the corresponding balls 34. With this arrangement, it will be appreciated that there need not be perfect alignment and parallelism between the guide blocks 28 on opposite sides of the tank since the bridge 30 is guided for rectilinear movement at the shoe 40 and shoe 42 is permitted to shift transversely relative to guide block 28 at the opposite side of the tank. This feature of the present arrangement is especially important in connection with tank warpage or deflection due to hydrostatic forces. It is common for side walls of plating tanks to deflect and buckle slightly, and for this reason, absolute alignment and parallelism of the guide blocks on opposite sides of the tank is often difficult.

The shoes 40 and 42 are each fashioned with an extension 48 which projects inwardly over the tank. At their inner ends, extensions 48 are provided with a mounting flange 50 having downwardly and inwardly inclined side faces 52 (Fig. 6). Channels 54, one for each of the rails 14, are adjustably secured to the mounting flanges 50, preferably by means of depending lugs 56 and 58 on the underside of channels 54. A round rod 60 is welded to the inner face of lug 56 and a locking screw 62 is threaded through the other lug 58 so that when screw 62 is tightened, the channel 54 is securely mounted on the mounting flange 50. Within channels 54 are welded a plurality of spaced support blocks 64 provided with up-

right lugs 66. Rails 14 are secured to lugs 66 as by screws 68. Supports 64 serve as rest pads for rails 14 and at the same time serve as spacers which increase the section modulus of the composite structure formed by rail 14 and channel 54.

Guide blocks 28 are mounted on base plates 24 for adjustment inwardly and outwardly of the side walls of the tank. Thus, base plates 24 are each fashioned with a stop 70 and an upright lug 72 between which the guide blocks 28 are arranged. Adjoining and locking screws 74 are threaded through lug 72 and have their ends engaging bearing plates 76. Guide blocks 28 are adapted to be clamped between stops 70 and bearing plates 76 by tightening screws 74. When the screws 74 are loosened, the guide blocks 28 are adapted to be shifted transversely of base plates 24 and thereafter rigidly clamped in position by again tightening screws 74. In applications where rails 14 are electrified, which is ordinarily the case in plating tanks, insulating spacers 78, 80 and 82 are located at each end of and beneath guide blocks 28 to effectively insulate the bridge assembly 30 from the tank structure when balls 34 are formed of electrical conducting material.

Each pair of base plates 24 has also mounted thereon a stationary bridge 84. The stationary bridges 84 provide substantial lateral support for the side walls of the tank and reduce materially the extent of reinforcing bracing required such as the stiffeners shown at 85. In addition, one of the stationary bridges 84 has a pair of bearing blocks 86 mounted thereon in which a shaft 88 is journaled. A pair of levers 90 fixed at one end on shaft 88 are pivotally connected to the ends of links 92. Links 92 are in turn connected to shoes 40 and 42 as by the clevis structure 94. Link 92 includes an insulating coupling 95 so as to insulate the movable bridge assembly from the mechanism that actuates it. Shaft 88 is arranged to be oscillated so as to reciprocate the movable bridges 30 and therefore the rails 14 by means of a crank arm 96 fixedly mounted on shaft 88 and which is provided with an offset as shown in Fig. 1 so that the free end of the crank arm is located above and is offset from the vertical projection of the tank 10. Crank arm 96 connects with a link 98 which is in turn connected to an eccentric 100 driven by a motor 102 through a reduction gearing 104. The eccentric 100 may be adjustable so as to vary the throw of crank 96 and thus the extent of reciprocation of rails 14. Motor 102 and reduction gearing 104, it will be noted, is located outside the tank where it will not be subjected to corrosion. Ordinarily, an overall stroke of rails 14 of about three inches is sufficient to effectively maintain the work pieces substantially free of hydrogen bubbles.

As mentioned previously, at each end of the tank, an elevator structure is provided for transferring the work carriers 16 from one tank to the next adjacent tank. In order to maintain the transfer distance between tanks accurate at all times, it is necessary to provide at the end of the tank a mechanism for trapping the work carrier in a predetermined position and holding the work carrier in that position while the rails 14 are reciprocating. In the present arrangement, this trap mechanism includes a pair of latch members 106 which are pivotally supported as at 108 on adjustable supporting brackets 110 arranged to be clamped to the support flanges 13 of the tank. The latch members 106 are supported one each along side rails 14 and are counterbalanced as at 112 so that they normally pivot to a position wherein the inclined end 114 is pivoted downwardly by engagement with portions of the carriers 16; and when the carrier reaches said predetermined position, the latch members 106 pivot upwardly to effectively trap the carrier between shoulders 116 and 118 on the latch members 106. There is also mounted on each bracket 110 a rail supporting block 119 which supports the end portion of the rail both laterally and vertically.

With the above arrangement, the work carriers 16 are successively engaged by the reciprocating pusher assemblies 18 and are pushed with a step-by-step movement along the rails 14. The pusher assemblies 18 advance the work through each tank and thus control the advancing movement of the work carrier 16 on the rails 14. However, when the pusher assemblies disengage the work carriers 16, then the work carriers are free to reciprocate in the tank with the rails 14.

It is believed that the advantages and the improved features of the present arrangement for reciprocably supporting the rails over a plating tank are readily apparent from the foregoing description. For example, since the movable bridges 30 are guided for rectilinear movement only at one side of the tank, the whole bridge structure including the rails 14 behave as a single unitary structure and the distance between the rails is maintained constant at all times even if there is a deflection in the side walls of the tank. In other words, the rail supporting structure is enabled to shift as a whole without changing the distance between the rails.

It will also be appreciated that the particular manner in which the movable bridges 30 are movably mounted on the tanks is highly desirable. Rolling friction alone is encountered, and the use of balls for this purpose reduces friction to a minimum. This arrangement is far superior to the type wherein a roller is mounted on a pin, the latter eventually presenting difficulties because of wear, corrosion, dirt and the like. Furthermore, it will be noted that substantially no moving parts are disposed directly above the plating solution within the tank. These moving parts are mounted on the support flanges 13 along each side of the tank. The use of the channels 54 underlying each rail is also highly desirable. These channels not only collect the metallic particles loosened by the rubbing of the carrier on the rails, but also contribute toward the making of a composite structure. The channels 54 reinforce the rails 14 and make it possible to space the sets of stationary and movable bridges further apart than would otherwise be possible if the tendency of the rails to buckle is to be eliminated. It is also important to note that the arrangement here adapts itself admirably to easy fabrication and requires a minimum of fitting in the course of assembly at the customer's plant; and perhaps most important of all, it enables adjustment with a minimum of difficulty. Even though the side walls of the tank on which the support plates 24 are secured are not perfectly straight, perfect alignment of the rails can be obtained without any trouble. The guide blocks 28 on the guided side of the machine, that is, the side of the machine provided with the shoes 40, can be loosened and aligned with one another so that the rails as a unit will move in a perfectly straight path. After the blocks 28 on the guided side of the tank are aligned, the mechanism is thereafter self-compensating. Furthermore, even though the construction is not of the highly precision type, nevertheless, it acts as such because the weight of the reciprocating structure makes it bottom in grooves 32 and 44 and there is absolutely no side play.

I claim:

1. In a plating apparatus of the type including a tank and a work supporting rail extending lengthwise of the tank, means for reciprocating said rail comprising a bridge member spanning the tank and supporting the rail, a pair of guide members mounted one at each side of the tank, said bridge member having its opposite ends supported one on each of said guide members, rolling elements disposed between said ends of said bridge and said guide members for supporting said bridge on said guide members for movement longitudinally of the tank, at least one of said guide members being adjustable in a direction transversely of the tank and cooperating with the corresponding rolling element and one end of the

bridge to guide said end of the bridge in a rectilinear path lengthwise of the tank, the other end of the bridge being adapted to shift transversely relative to its guide member and means for reciprocating said bridge.

2. A plating apparatus as called for in claim 1 wherein said one guide member and said corresponding end of the bridge are fashioned with rectilinear guideways therein, the rolling element being engaged within said rectilinear guideways.

3. A plating apparatus as called for in claim 1 wherein said rolling elements are spherical in shape.

4. A plating apparatus as called for in claim 3 wherein the rolling element at said other end of the bridge is in rolling contact with a substantially flat horizontal surface.

5. In a plating apparatus of the type including a tank and a work supporting rail extending lengthwise over the tank, means for reciprocating said rail lengthwise of the tank comprising a pair of rigid inverted U-shaped bridge members spanning said tank and spaced lengthwise thereof, one of said bridge members being fixedly mounted on the side walls of the tank and the other having lower free ends of its legs supported on the opposite side edges of the tank for sliding reciprocating movement lengthwise of the tank and for adjustment in a horizontal plane transversely of the tank, a reciprocating mechanism mounted on the stationary bridge member and connected to the movable bridge member to reciprocate said movable bridge member in a horizontal plane when actuated, said rail being mounted on said movable bridge member, and power means positioned alongside of the tank and having a driving connection with said reciprocating mechanism.

6. A plating apparatus as called for in claim 5 including a pair of support plates fixedly mounted one at each side edge of the tank, said support plates having guide members mounted thereon for supporting the opposite ends of said movable bridge member, the ends of said stationary bridge member being fixedly mounted on said support plates.

7. A plating apparatus as called for in claim 5 wherein said power means is disposed below the level of the upper edge of the tank and said reciprocating mechanism includes a crank pivotally supported on said stationary bridge member, means connecting the crank with the opposite ends of the movable bridge and a link extending from said power means to the crank.

8. A plating apparatus as called for in claim 5 including a channel mounted on said movable bridge member in a position underlying said rail, said rail being mounted in said channel.

9. In a plating apparatus of the type including a tank and a work supporting rail extending longitudinally over the tank, means for reciprocably supporting said rail on said tank comprising a bridge spanning said tank transversely and supporting said rail, a guide member at each side of the tank on which the opposite ends of said bridge are supported, one of said guide members and the corresponding end of the bridge being provided with juxtaposed rectilinear guideways extending parallel to said rail and an anti-friction rolling element engaged in said guideways such as to restrict movement of the bridge to a direction parallel to said rail, the other end of the bridge being free to shift on its guide member in a direction transversely of the tank and means for reciprocating said bridge.

10. A plating apparatus as called for in claim 9 including a plate member fixed on said tank, said one guide member being mounted on said plate for adjustment in a direction transversely of the tank.

11. A plating apparatus as called for in claim 9 wherein said guideways comprise V-shaped grooves and said rolling element comprises a ball member.

12. A plating apparatus as called for in claim 9 where-

in said guideways comprise V-shaped grooves and said rolling element comprises a ball member formed of a hard material resistant to corrosion.

13. In a plating apparatus of the type comprising a tank and a pair of work supporting rails extending lengthwise over the tank, means for reciprocably supporting the rails comprising a pair of bridges spanning the tank and spaced longitudinally thereof, said rails being mounted on said bridges, guide members at each side of the tank for supporting the lower ends of each of said bridges and individual thereto, the guide members at one side of the tank being designed to restrict movement of the corresponding ends of said bridges in a rectilinear path lengthwise of the tank and the guide members at the other side of the tank cooperating with the corresponding ends of the bridges to permit said last mentioned ends of the bridges to move longitudinally of the tank and to shift in a direction transversely thereof, the guide members at said one side of the tank being adjustable in a direction transversely of the tank so that they may be brought into alignment with one another and means for reciprocating said bridges.

14. A plating apparatus as called for in claim 13 wherein said rails serve to interconnect said two bridges and said reciprocating means are connected to one of said bridges.

15. A plating apparatus as called for in claim 13 wherein said guide members at said one side of the tank comprise blocks having V-shaped guideways therein, the corresponding ends of said bridges also having V-shaped guideways therein and including rolling elements disposed between said guideways.

16. A plating apparatus as called for in claim 13 wherein said rails are mounted on said bridges for adjustment in a direction transversely of the tank.

17. A plating apparatus as called for in claim 13 including channels underlying each of said rails and extending lengthwise thereof, said rails being mounted one in each of said channels and said channels in turn being mounted on said bridges.

18. A plating apparatus as called for in claim 13 including a pair of stationary bridges spanning the tank and fixedly mounted one adjacent each of said movable bridges, said reciprocating means being mounted on one of said stationary bridges and connected to the adjacent movable bridge.

19. A plating apparatus as called for in claim 18 wherein said reciprocating means comprises a crank assembly mounted on said stationary bridge adjacent one side of the tank and a power unit along said side of the tank connected with said crank assembly.

20. In a plating apparatus of the type comprising a tank and a pair of work supporting rails extending lengthwise over the tank, means for reciprocably supporting said rails comprising a pair of base plates mounted along opposite sides of the tank, the plates in each pair being spaced longitudinally of the tank and aligned transversely with the base plates on the opposite side of the tank, a pair of movable bridges spanning said tanks and having their lower ends supported one on each of said base plates, a pair of stationary bridges spanning said tank and fixedly mounted on said base plates one adjacent each of said movable bridges, said base plates each having a guide member thereon for supporting the lower ends of said movable bridges, the guide members on the base plates at one side of the tank having a rectilinear guideway therein and the corresponding ends of said movable bridges also having a rectilinear guideway therein, rolling elements disposed between said guideways for restricting movement of said last mentioned ends of the bridges in a direction longitudinally of the tank, said last mentioned guide members being movably mounted on said base plates for adjustment in a direction transversely of the tank so that the guideways therein can be brought into alignment with one another, the guide members on

the opposite side of the tank cooperating with the corresponding ends of said movable bridges to permit said last mentioned ends of the bridges to move longitudinally of the tank and to shift in a direction transversely thereof, said rails being mounted on said movable bridges and means for reciprocating said movable bridges.

21. A plating apparatus as called for in claim 20 wherein said rails are mounted on said movable bridges for adjustment in a direction transversely of the tank.

22. A plating apparatus as called for in claim 20 wherein said reciprocating means comprises a crank assembly mounted on one of said stationary bridges at one side of said tank, a power unit at said one side of the tank disposed at a level below the upper edge of the tank and connected with said crank assembly, said crank assembly also being connected with the adjacent movable bridge.

23. A plating apparatus as called for in claim 20 wherein said base plates at said one side of the tank are each provided with a guideway extending in a direction transversely of said rails, said guide members being disposed in said last mentioned guideways with the guideways in the guide members extending parallel to said rails, said guide members being shiftable in said guideways in the base plates in a direction toward and away from said rails and means on said base plates for clamping said guide members in an adjusted position therein.

24. A plating apparatus as called for in claim 20 wherein said rails are arranged to slidably support work carriers, means adjacent one end of the tank for engaging a work carrier on said rails in a predetermined position relative to the tank and for holding said work carrier in said predetermined position relative to the tank while said rails are being reciprocated longitudinally of the tank.

25. A plating apparatus as called for in claim 24 wherein said last mentioned means comprises a pair of latches pivotally supported on said tank, one adjacent each of said rails, said latches each having a pair of spaced shoulders thereon adapted to engage opposite edges of the work carrier to prevent movement of the work carrier in a direction longitudinally of the tank when engaged with said latches.

26. In a plating apparatus of the type including a tank and a pair of work supporting rails extending lengthwise over the tank, means for reciprocating said rails in unison comprising a bridge spanning the tank, said rails being supported one adjacent each of the opposite ends of said bridge, a pair of guide members mounted one adjacent each side of the tank and spaced from the end of the tank, said rails extending to adjacent said end of the tank, said bridge having its opposite ends supported one on each of said guide members, rolling elements disposed between the ends of the bridge and said guide members for supporting the bridge on the guide members for movement longitudinally of the tank, means for reciprocating said bridge whereby to reciprocate said rails lengthwise of the tank, said rails being adapted to slidably support work carriers that are pushed along said rails towards said end of the tank and means adjacent said end of the tank for engaging the work carrier on said rails when it reaches a predetermined position adjacent said end of the tank and for holding said work carrier in said fixed position relative to the tank.
27. A plating apparatus as called for in claim 26 wherein said means comprises a pair of brackets mounted one on each of the opposite sides of the tank adjacent said end thereof and a pair of latches pivotally supported one on each of said brackets, said latches being arranged to engage a work carrier on said rails and prevent movement thereof in a direction longitudinally of the tank.
28. A plating apparatus as called for in claim 27 including means on said brackets slidably engaging the end portions of said rails.
29. A plating apparatus as called for in claim 28 wherein said last mentioned means are designed to support said end portions of the rails both vertically and laterally.
